UNITED STATES PATENT OFFICE

133,921

DESIGN FOR A STORE FRONT

Francois Uldege Dumas, Spencer, Mass.

Application June 2, 1941, Serial No. 101,257

Term of patent 14 years

To all whom it may concern:

Be it known that I, Francois Uldege Dumas, a citizen of the United States, residing at Spencer, in the county of Worcester and State of Massachusetts, have invented a new, original, and ornamental Design for a Store Front, of which the following is a specification, reference being had to the accompanying drawing, forming part thereof.

Fig. 1 is a view in front elevation; and

Fig. 2 is a view in side elevation looking in the direction of arrow 2 in Fig. 1 of a store front, showing my new design.

I claim:

The ornamental design for a store front, as shown.

FRANCOIS ULDEGE DUMAS.

CERTIFICATE OF CORRECTION.

Design No. 133,921.

September 29, 1942.

FRANCOIS ULDEGE DUMAS.

is hereby certified that error appears in the above numbered patent requiring correction as follows: In the heading to the drawing, line 2, for "STOVE FRONT" read --STORE FRONT--; and that the said Letters Patent should be read with this correction therein that the same may conform to the record of the case in the Patent Office.

Signed and sealed this 16th day of March, A. D. 1943.

Henry Van Arsdale,
(Seal) Acting Commissioner of Patents.
